AUTOMATIC SHEET FEEDING DEVICE FOR
DUPLICATORS

Frederick W. Storck, Arlington, and Paul T. Trueman, Canton, Mass., assignors to Standard Mailing Machines Company, Everett, Mass., a corporation of Massachusetts

Application May 2, 1936, Serial No. 77,578

8 Claims. (Cl. 271—42)

This invention relates to improvements in feeding devices adapted for use with rotary duplicators having a master copy for imparting same to clear sheets subsequently engaged therewith and the invention more particularly relates to 5 a sheet feeding mechanism associated with the duplicator for automatically feeding the top sheet of a stack to be duplicated upon for registering engagement with the master copy.

In rotary duplicators of the referred to character, it is essential that the clear sheet to be duplicated upon be aligned with respect to the master copy during the forward feeding movement of the sheet so as to render the machine adaptable for use with sheets having specific portions on which the matter of the master copy must register as the sheets are engaged therewith.

In the present type of sheet feeding device, and 20 to which our improvements pertain, the sheets to be duplicated upon are placed upon a tray or support in a stacked formation against a stop which engages the advance end of the stack. Stops of this character have heretofore been provided 25 with a spring pressed flange portion which overlies and engages a margin of the uppermost sheet of the stack under pressure and, as the stack is decreased, the flange descends in engagement therewith while, in other devices, 30 mechanism is provided for lifting the stack supporting platform bodily to retain the uppermost sheet in engagement with the referred to overlying flange. These known devices usually employ a roller, mounted to be bodily reciprocated above 35 the stack and in contact therewith and intermittently locked against rotation so as to intermittently become a pusher for the uppermost sheet of the stack. The roller is locked against rotation, during a portion of this reciprocating movement, in a manner to first move the top sheet 40 backward from under the forward end stop flange and then propel the sheet forward over the stop flange into engagement with the duplicating means.

In sheet feeding devices of the referred to character, of which we are aware, various complicated and exposed means have been utilized to arrest 45 rotative movement of the feed roller such as, for example, reversible or double acting ratchets and pawls which are affixed to or associated with the ends of the roller or act directly on the roller shaft to which the roller or like members are secured.

Therefore, one of the objects of our present 50 invention is to provide a sheet feeding device

that is efficient and simple in construction and which incorporates substantially enclosed unit devices for causing positive feeding of the sheet from a stack to registering engagement with the master copy.

It has been a special object of our invention to provide an automatic sheet feeding device with improved means for intermittently engaging directly with the feed roller for locking the feed roller against rotation and in a manner so as to 5 provide accuracy of operation which adapts our device for use where exact alignment and positioning of the sheet is required and in a manner that requires a minimum of attention on the part of the operator.

Another object is to provide a feeding roller unit, including a control for arresting rotative movement of the roller, so constructed that the unit may be moved bodily crosswise of the stack, and positioned as desired for engagement with 10 the uppermost sheet of the stack.

A further object is to so construct our feeding roller unit so as to permit the use of a plurality of separate units, should occasion require the use of more than one unit, for engagement with the 15 uppermost sheet of a stack and wherein the locking function of each unit may be adjusted independent of the other.

A still further object is to construct our feeding roller unit so that the feed roller of the unit will 20 be independently self-aligning relative to the plane of the stack.

With the above and other objects in view, our invention comprises a novel combination and arrangement of parts hereinafter described and 25 more specifically pointed out in the appended claims.

In the accompanying drawings we have shown 30 our invention sufficient to enable those skilled in the art to understand the construction and 35 operation thereof.

While we have shown our feeding device associated with a duplicator as described in U. S. Letters Patent No. 1,964,933, it is to be understood 40 that this is for the purpose of illustration only and our device is not to be limited to a machine of this specific construction; and further, our illustrated embodiment shows a feeding device employing two of our units, but it is to be understood that a single unit with a roller of required 45 length may be utilized to effectively feed a sheet from the stack.

In the drawings which illustrate an embodiment of our feeding device and wherein like reference characters are used to designate like parts:

Fig. 6 is a view corresponding substantially to Fig. 5, but shows some of the parts in a different position.

Fig. 7 is a detail of the intermittent gears as embodied in the illustrated duplicating machine.

Fig. 8 is a sectional view of a modified form of our feed roller and carriage illustrated at Fig. 5.

Fig. 9 is a view corresponding substantially to Fig. 8, but shows some of the parts in a different position.

Fig. 10 is a detail of our shaft actuating arm and its movement limiting pin.

30 The duplicating machine

The duplicating machine as illustrated is provided with opposed stationary side frames 10 which support the operating elements of the duplicator. The frames are retained in a spaced relation by suitable cross members (not shown).

The printing platen 11 is rotatably mounted upon a shaft 12 which, in turn, is secured against rotation in suitable bearings in the side frames. The printing platen 11 is provided with a suitable clamping device 13 for holding the end of the master copy.

A pressure roller 14 engages the peripheral face of the platen 11 and is mounted upon a shaft 15 which is journaled at its ends in suitable bearings in the side frames.

The feed rollers 16 and 17 are each provided with shafts 18, 19 which are rotatably supported in suitable bearings. In this instance, the roller 16 is utilized as an intermediate moisture applicator which is supplied with moisture by a wick 20 which engages with fluid contained in the tank 21.

The duplicator drive

55 The mechanism for intermittently rotating the printing platen includes a primary gear 22 which is adapted to be continuously rotated as, for example, by means of a continuously driven pinion (not shown) which, in turn, may be actuated by a hand crank or power driven. An intermittent gear 23 is secured to the primary gear 22 and meshes with a coacting intermittent gear 24 secured to the drum or platen 11. The gears 22 and 23 are rotatably mounted on a stud 25, which is secured to one of the side frames 10. The intermittent gears 23 and 24 are of the usual construction wherein a predetermined portion of the periphery of each is free from teeth and continued rotation of the driving gear will not rotate the driven gear until the blank space in the driving gear has passed the blank space in the driven gear and the teeth in both enmesh. Fig. 7 illustrates the construction of the intermittent gears 23 and 24.

75 The feed rollers 16 and 17 are intermittently

rotated with the printing platen 11 by means of a gear 26 which is secured to one end of the platen. This gear 26 enmeshes with and drives an intermediate gear 27 which, in turn, enmeshes with and drives a pinion 28 adapted to rotate the feed roller 16, the coating roller being frictionally driven.

5 A duplicating machine of the above character is fully shown and described in the aforesaid patent, therefore, further detailed description of 10 the parts and operation thereof is thought unnecessary.

The sheet stack support

The stack of sheets 29 to be duplicated upon 15 is supported upon a tray 30 which, in this instance, is provided with upwardly extending side flanges 30a. The advance ends of the flanges 30a are secured to a transverse rod 31 which extends beyond the flanges and engages in slotted 20 bearings 10a in the side frames to support the advance end of the tray in a positioned relation to the feed rollers 16 and 17. The rear end of the tray is supported by a knee brace 32 pivoted at 33 to the tray and engaging a cross rod 10b 25 disposed in and between the side frames.

The advance end of the tray 30 is provided with a stop 34 having inwardly extending flanges 34a, 34b. The lower flange 34a acts as a stop for the end of a pressure plate 35 which is pivoted at 36 to the bottom of the tray 30 and forms a part thereof. This pressure plate 35 is provided with an extension 35a which is adapted to engage one end of a compression spring 37, the opposed end of said spring 37 having its bearing 35 against the under side of the tray 30. The spring 37 urges the forward end of the pressure plate in the direction of the top flange 34b, of the front stop 34, and thus, as the stack is reduced, the uppermost sheet is always engaged under pressure with the under side of the flange 34b and facilitates withdrawing a single uppermost sheet of the stack as will be hereinafter mentioned. Further, with this arrangement of parts, the top flange 34b is always positively positioned 45 relative to the engaging point of the feed rollers and, therefore, each sheet to be subsequently fed is disposed to require like feeding movement for engagement by the feed rollers 16, 17.

The sheet feeding device

When in operative position, the feed roller 38 is continuously in contact with the top of the stack 29. This roller may be of any suitable construction provided with a frictional face and we preferably use a roller having a serrated or like rubber face as illustrated at Figs. 5 and 6. The feed roller 38 is rotatably mounted in a frame 39 which is provided with a sleeve 39a. This sleeve 39a is mounted for slight rotative movement on the trunnion 40a of a bearing 40 and its movement thereon limited by stop screws 41.

The frame bearing 40 is mounted on a transverse shaft 42, having its opposed ends mounted in anti-friction bearings 43 secured in the upper ends of oscillating levers 44 and 45, the lower ends of said levers being secured to the cross rod 10b and pivoted therewith. The levers 44 and 45 are oscillated by means of an arm 46 having one end pivoted at 47 to the lever 45 and its opposed end pivoted to a crank disc 48 adjustably secured on a 70 shaft 48a which has secured thereto a gear 49 which meshes with the primary gear 22 and thus the levers 44, 45 are oscillated in a direct and timed relation to the aforementioned dwell period 75 of the intermittent gears 23, 24.

The feed roller lock

The shaft 42 is provided with a longitudinal groove 42a which, together with the peripheral face of the shaft, may be conveniently said to form a cam face for a purpose hereinafter mentioned. This groove 42a is adapted to receive the head 50a of a cam follower plunger 50 which is slidably mounted in an enlarged cylindrical bore in the bearing trunnion 40a. The plunger 50 is retained in contact with the shaft 42 by means of compression spring 51 which has its bearing at one end under an annular head 50b, of the plunger, and its opposed end bearing against the end of the enlarged cylindrical bore in the trunnion 40a. Rotative movement of the plunger 50, within the trunnion 40a, is prevented by means of a slot 50c, formed in the plunger, which slidably engages with a pin 40b secured in the trunnion.

The plunger 50 is provided with a threaded bore 50d adapted to engage the threaded portion of an adjusting screw 52. In this instance the inner end of the screw is split and expanded, as is well known, to prevent free rotative movement of the screw. It is obvious that other forms may be employed for locking the adjusting screw in a desired position.

This adjusting screw 52 is provided with an enlarged head 52a and is adapted to freely support a brake-head member 53, and, by means of this screw, the disengaged spaced relation of the brake-head relative to the roller 38 may be adjusted. The brake-head member 53 is urged against the screw-head 52a by means of a compression spring 54 which encircles the screw 52 and has its bearing at one end against the screw-head 52a and its opposed end bearing against the bottom of a cylindrical bore in the plunger.

Operation of feed roller lock

As the shaft 42 is rotated in the direction of the arrow, Fig. 6, as will be hereinafter described, the camming action of the shaft groove 42a against the plunger-head 50a causes the plunger to be moved to the right to engage the brake-head 53 with the face of the roller, see Fig. 6. Also, at the beginning of the shaft movement, this camming action of the shaft groove 42a against the head 50a causes a downward pressure to be exerted by the roller 38 and thus facilitates in the starting of a gripping action upon the uppermost sheet by the locked roller.

The complete movement of the plunger 50 is greater than is required to cause contact between the brake-head 53 and the face of the roller 38. This greater movement of the plunger 50 causes the brake-head 53 to become unseated, relative to the enlarged screw-head 52a, and compresses the spring 54 against the brake-head, thus causing the brake-head 53 to be forced into a yielding pressure engagement with the roller 38 and thus locking the roller against rotation. Also, this spring 54 compensates for any wear which might occur on the face of the feed roller. As is obvious, the degree of yielding pressure, of the compression spring 54, is controlled by the strength of the spring and which may be selected to suit conditions. It should be noted that the bores in the brake-head 53 are provided with sufficient clearance so as to substantially effect a floating or self-aligning contact of the brake-head with the roller face under the influence of the compression spring 54.

Conversely, as the shaft is rotated in the direc-

tion of the arrow, Fig. 5, the spring 51 urges the plunger-head 50a into the groove 42a and, through the screw-head 52a the brake-head 53 is disengaged from its relation with the roller, the spring 54 again seating the brake-head 53 against the screw-head 52a and thus the roller 38 is again free to rotate.

Modified form of feed roller lock

At Figs. 8 and 9 we have shown a modified form of locking device for the roller 38 and in which the cam follower is in the form of a pin 70 having an enlarged head 70a which is adapted to engage in the shaft groove 42a. This pin 70 is slidably mounted in a plunger 71, which, in turn, is slidably mounted in the cylindrical bore in the bearing trunnion 40a. The cam follower 70 is urged in the direction of the shaft 42 by means of a compression spring 72 which has its bearing at one end under the enlarged head 70a of the pin 70 and its opposed end bearing against the bottom of the bore in the plunger 71. Movement of the pin 70, under the influence of the spring 72, is limited by means of a cross-pin 73 which is secured in the pin 70 and has its extending ends engaging in opposed slots 71a in the plunger 71. This plunger 71, together with the cam follower pin 70, forms a unit which may be conveniently termed—a yielding plunger unit.

A compression spring 74, of a lesser strength than the pin spring 72, encircles the plunger 70 and has its bearing, at one end, under an annular head of the plunger 70, the opposed end of said spring 74 having its bearing against the bottom of the enlarged cylindrical bore in the trunnion 40a. This spring 74 urges the plunger unit into engagement with the shaft 42.

The plunger 71 is provided with a pin 75 which slidably engages in a slot 40g, in the trunnion 40a, and thus prevents rotation of the plunger. The outer end of the plunger 71 is threaded in a manner to have adjustably secured thereon a brake-head 76; this threaded portion may be split and expanded, as is well known, in providing this form of a frictionally controlled adjustment, or any other suitable means may be provided to retain the head 76 in an adjusted position relative to the face of the feed roller 38. This means of adjustment, or means as illustrated in our preferred form, permits the use of more than one unit in feeding a sheet and each unit may be independently adjusted in its braking action to arrest movement of the roller 38 in a manner to prevent skewing of the sheet and assure accuracy in alignment as the sheet is advanced during the feeding operation. It is apparent that without this independent adjustment, feeding stresses on opposite sides of the sheet could not be equalized when more than one unit is used.

Operation of the modified form of feed roller lock

With our modified construction, as the shaft 42 is rotated in the direction of the arrow, Fig. 8, the camming action of the shaft groove 42a against the pin-head 70a causes the weaker plunger spring 74 to be compressed first and the plunger unit moved to engage the brake-head 76 with the face of the roller 38. After this initial engagement of the brake-head, further camming action of the shaft, in the completion of its movement, causes the cam follower pin-head 70a to compress its spring 72 and forms a yielding, pressure-exerting connection between the shaft 42 and the plunger 71 and thus, in turn, the

brake-head exerts a yielding pressure in its engagement with the roller face.

As the shaft 42 is rotated in the direction of arrow, Fig. 8, and, as the groove 42a registers with the head 10a of the cam follower pin 10, the pin spring 72 will move the pin 10 against its stop in the slot 75 and the plunger spring 74 moves the entire plunger unit to the left to its non-braking position with the pin-head 10a in engagement in the shaft groove 42a as illustrated at Fig. 8.

Operation of sheet feeding device

During the dwell period of the duplicator and its feed rollers, the stack 29 is placed on its support 30. During this dwell period, the feeding elements are positioned as shown by full lines, Fig. 2, and to facilitate in the positioning of the stack, the roller frame is adapted to be rotated about the shaft 42 to displace the roller 38 out of its engaging relation with the top of the stack, as illustrated by dot and dash lines in Fig. 2.

During the rotation of the roller frame in displacing the feed roller, as aforesaid, possible displacement of the shaft groove 42a from its operative position is prevented by means of a limiting pin 58a which is secured in one of the shaft supporting arms and engages in a cut-out 58b formed in the shaft arm 58, see Fig. 10. The rear end of the stack abuts against a stop 56 which extends under the stack 29 and thereby effects substantially a slight concave in the face plane of the stack which, in a measure, facilitates in operating upon the sheets.

At Fig. 2 the feeding device parts are shown as they are positioned at the limit of their forward movement which occurs during an interim of and in a timed relation to the dwell period of the duplicating machine and this position may be conveniently termed the beginning of the sheet feeding cycle.

To begin the cycle of feeding a single sheet, the arms 44, 45 are oscillated backward from the position shown in full lines, Fig. 2, to the position shown by broken lines, same figure, and during which the roller 38 is free to rotate in engagement with the top of the stack 29. As the arms 44, 45 continue their backward movement, the roller 51, of an arm 58 which is secured to the shaft 42, engages with an adjustable stop 59 and rocks the shaft 42 in a clockwise direction. This rocking of the shaft, through its groove 42a, operates the feed roller brake to arrest movement of the roller 38 by forcing the brake-head 55 into engagement therewith as aforesaid, and, as illustrated at Fig. 6. While the bodily rearward movement of the roller 38 is being completed, i. e., from the position shown by broken lines, Fig. 2, to the position shown in Fig. 1, the roller is locked against rotation in engagement with the uppermost sheet and causes the advance end of the uppermost sheet to be withdrawn from under the front stop flange 34 and the rear portion of the sheet is buckled against the rear stop 56, as illustrated at Fig. 1.

As the arms 44, 45 continue their oscillation, in a forward direction, the locked roller 38 acts as a pusher and advances the sheet, by its frictional engagement therewith, over the flange 34b and the forward end of the sheet is guided by a plate 60 into engagement, in this instance, with the bight formed between the feed rollers 16, 17 which are then in their dwell period. The sheet is slightly overfed, in being advanced, so as to form a slight buckle in the forward portion there-

of, so as to positively position the advance end as shown at Fig. 2.

When the arms 44, 45 approach the limit of their forward movement, the roller 51 engages with a forward adjustable stop 61 and, as the arms complete their forward movement, the shaft 42 is rotated in a contra-clockwise direction, thus effecting the unlocking of the feeding roller 38, as previously described and illustrated at Fig 5, and thus the feeding roller is free to rotate at the beginning of its backward bodily movement of its next successive cycle of operation.

Having thus described our invention, what we claim is:—

1. A sheet feeding device for duplicators having a support for a stack of sheets, a rockable shaft disposed above said stack with means for reciprocating said shaft bodily relative to said stack between opposed positions with a stop adjacent each of said positions, elements secured to said shaft and adapted to engage said stops and whereby said shaft is rocked to opposed positions, a frame having a bearing free for movement relative to said shaft, a rotatable roller mounted in said frame with slideable brake means carried by said frame and actuated by and through rotative movement of said shaft and whereby rotative movement of said roller is arrested for the purpose of feeding a sheet from said stack.

2. A sheet feeding device for duplicators including a support for a stack of sheets, a rockable shaft disposed above said stack with means for reciprocating said shaft bodily relative to said stack between opposed positions and a stop adjacent each of said positions, means cooperating with said shaft and stops whereby said shaft is rocked to opposed positions at determinate points in its reciprocating cycle, a bearing free for rotative and longitudinal movement relative to said shaft, a frame pivotally connected to said bearing, a rotatable roller mounted in said frame and in contact with the uppermost sheet of said stack when in operative position, spring pressed means carried by said bearing and controlled by said shaft upon the rocking thereof to arrest rotative movement of said roller for the purpose of feeding a sheet from said stack.

3. A sheet feeding device for duplicators including a support for a stack of sheets, a rockable shaft disposed above said stack with means for reciprocating said shaft bodily relative to said stack between opposed positions and a stop adjacent each of said positions, means cooperating with said shaft and stops whereby said shaft is rocked to opposed positions at determinate points in its reciprocating cycle, a frame rotatably supported by said shaft, a rotatable roller pivotally supported relative to said frame and adapted to engage with the uppermost sheet of said stack, a bore in said frame, a plunger slidably mounted in said bore with a spring member urging said plunger in the direction of said shaft, an adjustable member secured to the outer end of said plunger and adapted for engagement with said roller, a spring pressed member slidably mounted in said plunger and adapted for engagement with said shaft and whereby said slideable members are actuated to arrest rotative movement of said roller when said shaft is in one position and release said roller for rotative movement when said shaft is in an opposed position.

4. A sheet feeding device for duplicators which includes a support for sheets of paper to be du-

licated upon, a feeding roller in engagement with said stack, means for imparting to said roller a determinate forward and backward bodily travei movement relative to said stack with means embodying a rockable shaft and cooperative stops for effecting converse movement of said shaft for controlling the rotative period of said roller during said forward and backward travel.

5. A sheet feeding device for duplicators which includes a support for sheets of paper to be duplicated upon, a rotatable element in engagement with said stack with means for bodily moving said element forward and backward relative to said stack, together with a rockable shaft with 10 means for rocking said shaft at determinate points, and spring pressed means cooperating with said shaft and adapted, when in one position, to permit free rotative movement of said

element and, when in their opposed position, to arrest rotative movement of said element during a portion of its bodily movement.

6. A sheet feeding device as set forth in claim 5 wherein said rotatably mounted roller is self-aligning relative to the plane of said stack.

7. A sheet feeding device as set forth in claim 5 wherein said brake member is arranged to bear upon the surface of said roller with a yielding pressure.

8. A sheet feeding device as set forth in claim 5 wherein said brake member is arranged in an adjustable spaced relation relative to said roller during the disengaged period of said brake and roller.

10 FREDERICK W. STORCK.

PAUL T. TRUEMAN.
